UNITED STATES PATENT OFFICE.

JAKOB FUNCK, OF CHARLOTTENBURG, GERMANY, ASSIGNOR TO THE GRONDÅL KJELLIN COMPANY, LIMITED, OF LONDON, ENGLAND.

ELECTRIC INDUCTION-FURNACE.

1,226,764.

Specification of Letters Patent.

Patented May 22, 1917.

Application filed February 2, 1916. Serial No. 75,880.

To all whom it may concern:

Be it known that I, JAKOB FUNCK, a subject of the Emperor of Germany, residing at 8 Fredericiastrasse, Charlottenburg, in 5 the Empire of Germany, have invented certain new and useful Improvements in or Relating to Electric Induction-Furnaces of which the following is a specification.

This invention relates to electric induction furnaces, the chief object being to increase the durability of the linings of the hearths thereof by making the same much denser and harder than furnace linings formed in the usual manner. It has been 10 customary to form the lining of the hearth of an electric induction furnace by ramming the magnesite or similar material in a plastic condition around a templet arranged in the furnace hearth and after re- 15 moving the templet, consolidating or baking the mass by means of heating rings suitably arranged in the said hearth. This method of forming the lining is unsatisfactory as the lining expands owing to its exposure to the 20 air during the heating or sintering operation so that the density and hardness of the lining is detrimentally affected.

According to this invention the lining material is placed around a templet or former in the hearth of the furnace and the templet or former is then utilized for heating and consolidating the material and forming the lining *in situ*. In this manner air is 25 totally excluded from the lining during the heating operation and moreover the templet or former effectively prevents the lining material expanding during the sintering and setting thereof. Again, the exclusion of air from the lining material enables the binding 30 agent used therewith to be thoroughly coked and not burned on the surface of the lining as would be the case if the material were exposed to the air during the heating operation.

45 In order that the invention may be clearly understood and readily carried into effect the same will now be more fully described by the aid of the accompanying drawing, in which:—

50 Figure 1 is a plan of a furnace showing the templet and lining in position.

Fig. 2 is a section on line A—A of Fig. 1 showing the lining rammed to the templet.

55 Fig. 3 is a fragmentary section showing a modification.

Fig. 4 a sectional view of the templet.

The templet or former *a* employed is made of metal and conforms with the shape of the furnace hearth. When the lining material *b* is in position the templet *a* closely fits and 60 entirely covers the inner surface thereof so as to effectively exclude air and prevent expansion during the heating operation. The dimensions of the templet *a* are such that when it is melted the resultant volume of 65 molten metal will be equal to the volume of the metal bath of the furnace, so that the molten metal will serve as the first charge for the furnace.

It is immaterial how the templet or former 70 *a* is constructed, that is, whether it consists of only one hollow piece provided with ribs *c* and occupying the whole hearth or whether it consists of several pieces provided with suitable reinforcements. It is 75 important however that the templet should extend to the upper edge of the lining and rest closely against the same. It may not always be desirable to have the metallic body of the templet or former in contact 80 with the lining of the furnace and in this case a layer of asbestos or similar material *d* may be interposed between the adjacent surfaces of the templet and lining see Fig. 3. The metallic body and enveloping shield of 85 asbestos or other material would then constitute the templet or former and in a similar manner to the arrangement previously described would effectively exclude air and prevent the expansion of the lining during 90 the heating operation.

What I claim and desire to secure by Letters Patent of the United States is:—

1. A method of lining the hearths of electric induction furnaces, consisting in placing the lining material around a templet in the furnace hearth, utilizing the templet for heating and consolidating the material to form the lining *in situ* and finally fusing the templet. 95

2. A method of lining the hearths of electric induction furnaces, consisting in placing the lining material around a templet in the furnace hearth so that the templet closely fits and entirely covers the inner surface of 105 the lining material utilizing the templet for heating and consolidating the material to form the lining *in situ* and finally fusing the templet to form the first charge for the furnace. 110

3. A method of lining the hearths of electric induction furnaces, consisting in placing the lining material around a templet comprising a single hollow metallic element arranged in the furnace hearth so that the templet closely fits and entirely covers the inner surface of the lining material, utilizing the templet for heating and consolidating the material to form the lining *in situ* and finally fusing the templet so that the metal thereof, when in the molten state, constitutes the initial metal bath for the furnace.
4. A method of lining the hearths of electric induction furnaces, consisting in placing the lining material around a templet comprising several hollow metallic elements with suitable reinforcements arranged in the furnace hearth so that the templet closely fits and entirely covers the inner surface of the lining material, utilizing the templet for heating and consolidating the material to form the lining *in situ* and finally fusing

the templet so that the metal thereof, when in the molten state, constitutes the initial metal bath of the furnace.

5. A method of lining the hearths of electric induction furnaces, consisting in placing the lining material around a metal templet which is provided with an enveloping sheath of asbestos or similar material, utilizing the templet for heating and consolidating the material to form the lining *in situ* and finally fusing the templet.

6. A method of lining the hearths of electric induction furnaces, consisting in placing the lining material around a metal templet which is provided with an enveloping sheath of asbestos or similar material so that the templet closely fits and entirely covers the inner surface of the lining material, utilizing the templet for heating and consolidating the material to form the lining *in situ* and finally fusing the templet.

JAKOB FUNCK.
